CLAIM

The ornamental design for fishing lure article, as shown and described.

DESCRIPTION

FIG. 1 is a top plan view of the fishing lure article of the present invention;

FIG. 2 is a side elevation view thereof;

FIG. 3 is a bottom plan view thereof;

FIG. 4 is a front elevation view thereof;

FIG. 5 is a rear elevation view thereof; and,

FIG. 6 is a perspective view thereof.

The broken lines depict environmental structure and are included for illustrative purposes only and forms no part of the claimed design.
